UNITED STATES PATENT OFFICE

VACLAV J. HAJNY, OF BROOKFIELD, ILLINOIS

DESIGN FOR A CASKET BIER

Application filed August 21, 1930. Serial No. 36,724. Term of patent 3½ years.

To all whom it may concern:

Be it known that I, VACLAV J. HAJNY, a citizen of the United States, residing at 3636 Forest Avenue, in the village of Brookfield, county of Cook and State of Illinois, have invented a new, original, and ornamental Design for a Casket Bier, of which the following is a specification, reference being had to the accompanying drawing, forming a part thereof.

Fig. 1 is a side elevation of a casket bier embodying my new design.

Fig. 2 is an end elevation of the casket bier shown in slightly reduced scale.

I claim:

The ornamental design for a casket bier, as shown.

VACLAV J. HAJNY.
